TELEPHONE SYSTEM

Clarence Ernest Lomax, Oak Park, Ill., assignor to
Associated Electric Laboratories, Inc., Chicago,
Ill., a corporation of Delaware

Application April 22, 1940, Serial No. 330,977

38 Claims. (Cl. 179—27)

The present invention relates to telephone systems and more particularly to improved apparatus for setting up reverting call connections between two substations associated with the same multiparty subscribers line.

In existing telephone installations no provisions are made for informing the recipient of a reverting call as to the type of call being answered. More particularly, two methods of handling reverting calls are extensively used in systems of the automatic type. According to one of these methods, commonly known as the directory number dialing method, the calling subscriber, after dialing the directory number of the called substation, restores his receiver to its supporting hook or cradle, and after waiting a reasonable time interval again removes his receiver from its supporting hook or cradle to prepare or complete the desired connection, depending upon whether the call has been answered at the called substation. If, during this interval, the call is answered at the called substation, the answering party receives the impression of a dead line, due to the fact that he receives no response to his answering salutation. The other method commonly used in handling reverting calls in automatic systems is that of providing reverting call switches for selective ringing purposes. In practicing this method the substation associated with the multiparty subscribers lines are provided with special directory number listings. These special directory numbers must be dialed by calling subscribers in order to set up reverting call connections. This method is also open to the objection that a party answering a reverting call is not informed as to the character of the call and, accordingly, may assume that the call has been abandoned. The method of procedure followed in manual systems in handling reverting calls is also open to the disadvantage briefly outlined above.

It is an object of the present invention, therefore, to provide improved apparatus for setting up reverting call connections between the substations associated with the multiparty lines of a telephone system, which is so arranged that the character of reverting calls is indicated to the parties answering such calls.

It is another object of the invention to provide for use in an automatic telephone system an improved reverting call signaling arrangement which is equipped to transmit to an answering substation a signal indicative of the character of the call answered.

It is a further object of the invention to provide for use in a telephone system of the manual

type an operator's cord circuit which is equipped for selective signaling over multiparty lines and is so arranged that in handling a reverting call between two substations associated with the same line a special signal is transmitted over the line which indicates to the answering party the character of the call answered.

It is another object of the invention to provide an improved operator's cord circuit of the character described, wherein provisions are made for automatically releasing the selective signaling equipment when the answer plug of the circuit is withdrawn from a line jack.

It is still another object of the invention to provide in a telephone system of the manual type an improved disconnect signaling network which is so arranged that the line disconnect signal of the operator's cord circuit is only energized when a connection resulting from a call of the reverting type is released at both the calling and called substations.

It is a further object of the invention to provide improved apparatus of the character described, which is simple in arrangement, is positive and reliable in operation, and requires a minimum of circuit equipment.

The invention is illustrated in its embodiment in a system of the automatic type and also in a system of the manual type, both systems being arranged to serve subscribers lines of the multiparty type. In both systems, facilities are provided for selectively signaling the substations associated with the multiparty lines in setting up connections involving these lines, and each system includes, in accordance with the present invention, apparatus operative in response to the answering of a reverting call for indicating to the answering party that the answered call is of the reverting type. In the automatic system, this apparatus is included in a reverting call switch, which switch is accessible to certain of the selector or connector switches of the system and includes apparatus directly controllable over a connection routed thereto from a calling line of the system.

45 for impressing upon the calling line the one of a plurality of ringing voltages having the station indicating characteristic corresponding to a desired called substation served by the calling line. The reverting call switch further comprises 50 a ring cut-off relay and a slow-to-operate control relay which are sequentially operative in the order named in response to the answering of a reverting call at one of the substations associated with the calling line. These relays function to terminate the ringing operation and to transmit

a special signal of limited duration over the calling line for the purpose of informing the answering party that the answered call is of the reverting type.

In the disclosed embodiment of the manual system, the subscribers lines are terminated at line jacks provided at the operator's switchboard in the usual manner. An operator's cord circuit is provided at each operator's position which is adapted for use in setting up connections between the subscribers lines and is equipped with facilities for selectively signaling the substations associated with the multiparty lines of the system. More specifically, each cord circuit comprises an answer plug which is provided with a pair of line contacts and a control contact and is adapted to be inserted in the line jacks for the purpose of answering calls initiated on the subscribers lines. Each cord circuit has associated therewith a plurality of sources of ringing voltage having different station designating characteristics, and is equipped with a ringing voltage selecting switch. This switch has a normal setting and is selectively operable to any one of a plurality of off-normal settings to impress a selected one of the ringing voltages upon a calling multiparty subscribers line in handling a reverting call involving two of the substations served by the calling line. The cord circuit further includes apparatus operative in response to the answering of the call at one of the substations associated with the calling line for terminating the ringing operation and for transmitting a special signal of limited duration over the calling line to indicate to the answering party that the answered call is of the reverting type. Provisions are also made in the cord circuit whereby the ringing voltage selecting switch is automatically restored to normal in response to removal of the answer plug from the jack terminating the calling multiparty subscribers line. For the purpose of informing the operator when a reverting call connection established between two substations served by the same line is released, a disconnect signal device is provided which is so controlled that it is only energized in response to the release of the connection at both the calling and the called substations.

The novel features believed to be characteristic of the invention are set forth with particularity in the appended claims. The invention, both as to its organization and method of operation, together with further objects and advantages thereof will best be understood by reference to the specification taken in connection with the accompanying drawings in which Figures 1 and 2, when placed end to end in the order named, illustrate an automatic telephone system having embodied therein the features of the invention briefly outlined above, and Fig. 3 illustrates a telephone system of the manual type, also having embodied therein the features of the invention briefly referred to above.

Referring now more particularly to Figs. 1 and 2 of the drawings, the telephone system there illustrated comprises an exchange at which are terminated a plurality of subscribers lines, including the lines 10 and 11. The exchange comprises a plurality of finder-connector links, including the link 15, for setting up connections between the various subscribers lines. For the purpose of assigning idle ones of the finder-connector links to the use of calling lines in a predetermined order, a distributor 30 is provided. This distributor is arranged to be controlled over

5 a start circuit commonly extending to the various line circuits at which the subscribers lines are individually terminated, the two illustrated lines 10 and 11 being shown as extending to the line circuits 10a and 11a, respectively. Certain of the subscribers lines are of the multiparty type, each having associated therewith two or more substations. Thus, the subscribers line 10 is illustrated as being connected to provide service to the two substations A and B. The line 11, on the other hand, extends only to the substation C. For the purpose of selectively signaling the substations associated with the multiparty subscribers lines of the system in setting up reverting call connections, there are provided a plurality of reverting call switches, one of which is indicated generally at 35 as being accessible to the connector switch 25 over a trunk line 12. The switching equipment of the exchange has associated therewith power and supervisory apparatus which includes a ringing current generator 40 and a ringing interrupter 45. This apparatus may be of any desired construction and arrangement, it being pointed out that the ringing interrupter 45 is arranged to impress the voltage of the ringing current generator 40 upon the five ringing current leads for coded intervals which are different in each instance. Thus, differently coded ringing voltages are provided for the selective signaling of the substations served by the multiparty lines of the system.

Each of the links provided in the exchange may be identical with the link 15, which is illustrated as comprising a finder portion or switch 20 and a connector portion or switch 25, each having access to each subscribers line of the system. The finder switch and the connector switch included in each link may be of any conventional type, although preferably these switches are of the well-known Strowger type including two-motion switches for performing the line selecting functions. The connector portion of each link comprises impulse-responsive apparatus of any desired type for projecting ringing current of a selected code over an idle called multiparty subscribers line after the line has been seized by the switching mechanism included in the link. More specifically, each connector switch is arranged for switching through operation on calls to the lines forming predetermined groups such, for example, as calls routed to the trunks, extending to the reverting call switches. Each connector switch is also equipped with a code selecting switch which is directly controllable from any calling substation operatively to associate one of the five illustrated ringing leads with a selected side of a selected called line. The distributor 30 may be of any desired construction and arrangement, although preferably this control unit is of the preselective type such that an idle link is selected for assignment to the use of a calling line each time a previously selected link is rendered busy.

Each of the reverting call switches embodied in the system may be identical with the reverting call switch 35, which is illustrated in Fig. 2 of the drawings as comprising a minor switch 290 through operation of which ringing current of the code corresponding to a desired substation may be selected under the control of a calling subscriber. This switch is of the well-known minor type and includes two sets of contacts 291 and 292 of eleven points each, wipers 293 and 294 individually associated with the two contact sets, a motor magnet 295 for driving the wipers over the contacts of their associated contact sets,

a release magnet 296, and a set of off-normal springs 297 which are operative into engagement when the wipers 293 and 294 are moved off normal. The control equipment of the switch 35 comprises a line relay R220, a slow-acting hold relay R230, a slow-acting pulse-responsive relay R240, a ringing control relay R210, and a relay R200 which is operative to hold the switch operated during ringing periods. The control equipment further comprises a line switching relay R250, a control relay R260, a slow-acting ring cut-off relay R270, and a slow-to-operate signal control relay R280. The two last-mentioned relays are arranged to control a circuit, described hereinafter, for impressing the voltage of a special tone current source 46 upon an established connection which extends by way of one of the finder-connector links to a calling one of the subscribers lines. The source 46 may, if desired, comprise an alternating current generator having a predetermined output frequency such that a distinctive tone is produced when the output voltage thereof is reproduced.

In the operation of the system, if a call intended for the substation C, for example, is initiated at the substation A, a calling loop circuit is established by way of the line 10 when the calling subscriber removes the receiver provided at the calling substation from its associated supporting hook or cradle. When this loop circuit is completed, the line circuit 10a operates in the usual manner to mark the calling line in the bank contacts of the finder switches having access thereto, and to impress starting ground potential upon the start lead C13 extending to the link distributor 30. When this lead is grounded, the finder switch of the previously assigned link operates in a well-known manner to seize the calling line. Assuming that the finder-connector link 15 is utilized in setting up the connection, the wipers of the finder switch 20 are first elevated to a marked position opposite the level of bank contacts terminating the group of ten lines and including the calling line 10, following which they are automatically rotated to a position into engagement with the contacts terminating the conductors of this line. When the calling line 10 is thus seized, the calling loop circuit is extended to the connector portion 25 of the link, ground potential is impressed upon the private conductor of the calling line for the purpose of guarding this line against seizure, and the cut-off relay conventionally embodied in the line circuit 10a is energized and operates to disconnect the start lead C13 from ground. In addition, the line and hold relays embodied in the connector portion of the link operate to complete a marking path whereby the link is identified as busy in the link distributor 30. These relays, in operating, also function to impress ground potential upon the ringing apparatus start lead C41, thereby to initiate operation of the ringing current generator 40 and the ringing interrupter 45. These relays also operate to complete a circuit for transmitting the usual dial tone signal over the calling end of the connection, thereby to inform the calling subscriber that the dialing operation may be started. The first two digits dialed at the calling substation are utilized for the purpose of selecting the desired line 11. More specifically, when the first digit of the directory number designating the substation C is dialed, the wipers of the connector switch 25 are elevated to a position opposite the level of bank contacts terminating the group

of ten lines including the called line 11. The control relays of the link also operate to terminate the dial tone signal when the first digit is dialed at the calling substation. When the second digit of the directory number designating the desired substation C is dialed, the wipers of the connector switch are rotated step by step at the rate of one step for each impulse so that at the end of the digit they are left standing in engagement with the contacts terminating the conductors of the called line. Since the system is equipped for selective code ringing, a third digit must be dialed at the calling substation in order to condition the ringing control equipment embodied in the connector switch 25 for operation. At the end of this digit, the called line 11 is tested in the usual manner for the purpose of determining the idle or busy condition thereof. If the line 11 tests busy, the usual busy tone signal is transmitted to the calling substation to inform the calling subscriber that the desired connection cannot immediately be obtained. In this case, no further operation of the switching apparatus occurs until the call is abandoned at the calling substation. The link 15 and the line circuit 10a are released in the usual manner when the calling subscriber replaces the receiver provided at the calling substation upon its supporting hook or cradle. If the called line 11 tests idle, the control equipment embodied in the connector switch 25 operates in the usual manner to impress ringing voltage of the selected code upon the line 11, thereby to energize the ringer provided at the called substation C. This equipment also operates to transmit ringing current over the calling end of the connection to inform the calling subscriber that the called substation is being rung. The desired conversational circuit between the two substations A and C is completed when the call is answered at the called substation. More particularly, when the receiver provided at the called substation is removed from its supporting hook or cradle, a loop circuit is completed by way of the line 11 for energizing the ring cut-off relay conventionally embodied in the connector switch 25. This relay, in operating, opens the ringing current circuits and completes a talking circuit which extends through the link 15 and connects the calling line 10 with the called line 11.

Preferably, the arrangement of the control apparatus embodied in the connector switch 25 is such that the release of the connection is entirely under the control of the calling subscriber. As thus connected, when the calling party replaces the receiver provided at the calling substation A upon its supporting hook or cradle to interrupt the loop circuit extending to the connector switch 25, this switch, the finder switch 20, and the line circuits 10a and 11a are released in a conventional manner well understood in the art.

In the event the above-described call originating at the substation A and routed to the finder-connector link 15, is intended for the substation B, also associated with the calling line 10, the calling party, after initiating the call, dials a first digit designating the group of trunks extending to the reverting call switches, and then the last digit of the directory number designating the substation B. The connector switch 25 responds to the impulses of the first digit by elevating its wipers to a position opposite the level of bank contacts terminating the group of trunks, including the trunk 12, extending to the reverting call switches. During the inter-digit pause between

the first and second digits, the connector switch 25 operates in the manner of a trunk-hunting selector to select an idle one of the reverting call switches. Assuming that the reverting call switch 35 is the first available idle switch of the group, the connector switch 25, upon positioning its wipers upon the contacts terminating the conductors of the trunk 12, arrests its operation and extends the calling loop circuit over the trunk 12 to the switch 35. When this occurs, the line relay R220 is energized over the calling loop circuit and operates to complete, at its contacts 221, an obvious circuit for energizing the slow-acting hold relay R230. At its contacts 222, the relay R220 opens a point in the pulsing circuit, traced hereinafter, for energizing the slow-acting relay R240 in parallel with the motor magnet 295. The hold relay R230, in operating, opens, at its contacts 231, a point in the marking path including the resistor 236 over which negative battery potential is normally impressed upon the private conductor 12c of the trunk 12 to indicate an idle condition of the switch 35. At its contacts 232, the relay R230 completes an obvious path for impressing ground potential upon the private conductor 12c. When this conductor is connected to ground, locking circuits are completed for certain of the relays embodied in the connector switch 25, whereby this connector switch, the preceding finder switch 20, and the line circuit 10a are prevented from releasing. The application of ground potential to the conductor 12c further serves to mark the reverting call switch 35 as busy in the bank contacts of the other connector switches. At its contacts 233, the relay R230, in operating, prepares a locking circuit for the ring cut-off relay R270. At its contacts 234, the relay R230 prepares the above-mentioned circuit for transmitting current pulses to the magnet 295 and the relay R240 in parallel. At its contacts 235, the relay R230 opens a point in the operating circuit for the release magnet 296. Following the operation of the hold relay R230, the reverting call switch 35 is conditioned to respond to the impulses of the last digit of the directory number designating the desired substation B.

The line relay R220 follows the impulses of the second and final digit dialed at the calling substation A and functions to repeat these impulses to the operating magnet 295 in parallel with the relay R240, whereby the wipers of the ringing code selecting switch 290 are operated into engagement with the set of contacts corresponding to the ringing code assigned to the substation B and the side of the line over which ringing current must be projected in order to energize the signal device provided at the called substation. More specifically, when the relay R220 restores at the beginning of the open circuit period of the first impulse of the second digit, the above-mentioned circuit for energizing the relay R240 and the magnet 295, is completed. This circuit extends from ground by way of the contacts 222, 234 and 263, and the respective windings of the magnet 295 and the relay R240 in parallel to battery. When initially energized over this circuit the relay R240 operates to open, at its contacts 241, a point in the operated circuit for the relay R250. At its contacts 242, the relay R240 opens a point in the operating circuit for the line switching relay R250. The magnet 295 also operates when energized over the above-traced circuit, and in cooperation with its associated ratchet and pawl mechanism, not shown, functions to advance the wipers 293 and 294 from 75

their respective normal positions, illustrated in the drawings, into engagement with their respective associated first contacts. When these wipers are moved off normal, the off-normal springs 297 are operated into engagement to prepare the operating circuit for the relay R260.

As indicated above, the number of impulses in the final digit of the directory number designating the desired substation B depends upon the particular code assigned to this substation, and also upon the side of the line 10 to which the ringer provided at this substation is connected. Thus, if the ringer provided at the substation B is bridged across the line conductors 10a' and 10b in series with a condenser, and the code of the ringing current designating the substation B is the code 3, the wipers of the switch 290 may be operated to engage either their fifth or sixth contacts, and the ringer provided at the substation B will be energized during the ringing intervals. On the other hand, if the ringer provided at the substation B is connected in series with a condenser between the negative line conductor 10a' and ground, a final digit comprising five impulses must be dialed at the calling substation so that, at the end of the digit, the operating circuit for the line switching relay R250 is prepared. Finally, if the ringer provided at the substation B is connected in series with a condenser between the positive line conductor 10b and ground, a final digit comprising six impulses must be dialed at the calling substation.

Assuming that the ringer provided at the called substation is connected in the second manner described above, the line relay R220 operates and restores five times in response to the dialing of the digit 5 at the calling substation. Thus, five impulses are transmitted to the relay R240 in parallel with the operating magnet 295. Each time the line relay restores it opens the operating circuit for the hold relay R230 at its contacts 221. Due to the slow-to-release characteristics of the relays R230 and R240, these relays remain operated during impulsive. It will be apparent that at the end of the fifth impulse the wipers of the switch 290 are left standing in engagement with their respective associated fifth contacts so that the third ringing code is selected. Shortly following the end of the digit, and with the line relay R220 in its operated position, the slow-acting relay R240 releases to complete the prepared operating circuits for the two relays R250 and R260. The operating circuit for the relay R250 extends from ground by way of the multiplied odd-numbered contacts of the contact set 291, the wiper 293, the contacts 242, and the winding of R250 to battery. When energized over this circuit the relay R250 operates and locks to ground through the contacts 255 and the off-normal springs 297. At its contacts 251 to 254, inclusive, the relay R250 rearranges the ringing circuits for the transmission of ringing current over the negative side of the calling line 10. The operating circuit for the relay R260 extends from ground by way of the off-normal springs 297, the contacts 241 and the winding of R260 to battery. When thus energized, the relay R260 operates and locks to ground through the contacts 261 and the off-normal springs 297. At its contacts 263, the relay R260 opens the above-traced circuit for energizing the magnet 295 and the relay R240 in parallel. At its contacts 262, the relay R260 prepares an operating circuit for the relay R200.

After dialing the two digits of the reverting call directory number designating the substation B, the calling party at the substation A restores the receiver provided at this substation to its supporting hook or cradle, thereby to interrupt the loop circuit extending through the operated finder-connector link 15 to the reverting call switch 35. When this loop circuit is interrupted, the line relay R220 is deenergized and restores to open, at its contacts 221, the operating circuit for the hold relay R230. At its contacts 222, the relay R220 completes the prepared operating circuit for the relay R200, this circuit extending from ground by way of the contacts 222, 234, 262 and 275, and the winding of R200 to battery. When thus energized, the relay R200 operates to complete, at its contacts 204, a multiple circuit for impressing ground potential upon the ringing apparatus start lead C41, thereby to maintain the operation of the ringing current generator 40 and the ringing interrupter 45. At its contacts 203 (the relay R200 prepares a circuit for energizing the start ringing relay R210 when the ringing interrupter 45 next operates to impress a ground pulse upon the pick-up pulse lead C46. At its contacts 202, the relay R200 prepared a holding circuit for the relay R210. At its contacts 201, the relay R200 completes an obvious holding circuit for the slow-acting hold relay R230.

As indicated above, the ringing interrupter 45 is, in accordance with conventional practice, arranged to impress a ground pulse upon the pick-up pulse lead C46 at the beginning of each code cycle. The purpose of this arrangement is to prevent a partial or mutilated code from being transmitted over a selected called line. Following the operation of the relay R200, and when the ringing interrupter 45 next operates to ground the lead C46, the relay R210 is energized over a circuit including this lead, the contacts 203 and the contacts 216. When thus energized, the relay R210 operates and locks to ground through the contacts 215 and 202. After this locking circuit is completed, the relay R210 disconnects multiple ground from the pick-up lead C46 at its contacts 216. At its contacts 211 and 213, the relay R210 opens two points in the circuit for energizing the line relay R220. At its contacts 212 and 214, the relay R210 completes the ringing current circuit and connects the positive trunk conductor 12b to ground. Following the operation of the relay R210, ringing current is, during each ringing period of the selected ringing code, projected over the negative side of the calling line 10 to energize the ringer provided at the called substation. The path traversed by the ringing current may be partially traced as extending through the exchange battery and the ringing current generator 40, through the contacts of certain of the coding relays embodied in the interrupter 45 and by way of the code 3 ringing lead, the wiper 294, the upper winding of R270, the contacts 252 and 212, the conductor 12a, the line conductor 10a', and the series-connected ringer and condenser bridged between the conductor 10a' and ground at the substation B to the grounded terminal of the exchange battery. In the event the ringer provided at the called substation B is bridged between the conductors of the line 10 in series with a condenser, the return path of the ringing current extends by way of the line conductor 10b, the trunk conductor 12b, and the contacts 214 and 254 to the ground-

ed terminal of the exchange battery. In order more fully to explain the operation of the reverting call switch 35, it is pointed out that if a substation having a ringer bridged between the positive side of its associated line and ground is to be signaled through operation of this switch, an even-numbered final digit is dialed at the calling substation and hence the relay R250 is not energized at the end of the digit. With this relay in its restored position, the path of the ringing current extends by way of a selected one of the code leads, the wiper 294, the upper winding of R270, the contacts 253 and 214, and the trunk conductor 12b to the positive side of the calling line. In this case also, a ground return path extending over the trunk conductor 12a and through the contacts 212 and 251 is provided for completing the ringing current circuit in those instances where the ringer provided at the called substation is bridged across the conductors of the associated line.

When the call is answered at one of the sub-stations associated with the line 10, the control equipment embodied in the reverting call switch 35 operates to terminate the transmission of ringing current over the calling line and to transmit over this line a special signal of limited duration. Thus, if the call is answered at the called substation B, for example, a direct current bridge is connected between the conductors of the line 10 to complete the operating circuit for the ring cut-off relay R270. This circuit may take either of two forms depending upon the position of the relay R250. With the relay R250 in its restored position, the operating circuit for the relay R270 may be traced as extending from the negative terminal of the exchange battery by way of the ringing current generator 40, the contacts of certain of the coding relays embodied in the interrupter 45, the selected code 3 ringing lead, the wiper 294, the upper winding of R270, the contacts 253 and 214, the conductor 12b, the conductor 10b, the bridge across the conductors of the line 10 at the called substation, the conductor 10a', the conductor 12a, and the contacts 212 and 251 to ground. Alternatively, if the relay R250 is operated, the circuit for energizing the relay R270 extends by way of the code 3 ringing lead, the wiper 294, the upper winding of R270, the contacts 252 and 212, the conductors 12a and 10a', the bridge across the conductors of the line 10 at the called substation, the conductors 10b and 12b, and the contacts 214 and 254 to the grounded terminal of the exchange battery. When energized over either of the circuits traced above, the relay R270 first operates to complete a locking circuit for itself, this circuit extending from ground by way of the contacts 233 and 274 and the lower winding of R270 to battery. At its contacts 273, the relay R270 completes an obvious operating circuit for the relay R280. At its contacts 271, the relay R270 prepares a path for impressing the voltage of the special tone current source 46 upon the connection extending to the substation B. At its contacts 275, the relay R270 opens the previously traced operating circuit for the relay R200. The relay R200 now restores to open, at its contacts 204, the completed path for impressing ground potential upon the start conductor C41. At its contacts 203, the relay R200 opens a point in the operating circuit for the relay R210. At its contacts 202, the relay R200 opens the locking circuit for the relay R210. At its contacts 201, the relay R200 opens the locking circuit for the hold relay R230. The relay R210

restores in response to the release of the relay R200, and, at its contacts 211 and 213, again extends the loop circuit to the windings of the line relay R220. At its contacts 212 and 214, the relay R210 interrupts the previously traced circuits for transmitting ringing current over the line 10 and two points in the previously traced operating circuits for the ring cut-off relay R270. When its windings are again connected across the trunk conductors 12a and 12b, the line relay R220 is again energized and operates to recomplete the operating circuit for the hold relay R230. Thus, the hold relay R230 is prevented from restoring. At its contacts 222, the relay R220, in reoperating, opens a further point in the operating circuit for the relay R200. When the relay R210 restores it also functions to complete the above-mentioned path for impressing the voltage of the tone current source 46 upon the established loop circuit extending to the called substation B. This path may be traced as extending from the ungrounded terminal of the source 46 by way of the condenser 283, the contacts 281, 271 and 213 to the positive side of the connection extending to the substation B. The current traversing this path is transmitted through the windings of the receiver provided at the substation B, back over the negative side of the established connection and through the lower winding of the relay R228 to the grounded terminal of the source 46. The frequency of the current traversing this circuit is such that a distinctive tone is produced through operation of the receiver provided at the substation B. This tone serves to inform the answering party that the call which has been answered is a reverting call. Upon receiving this signal the answering party is informed that the answered call has not been abandoned, and further, that a short time interval may elapse before the calling subscriber again removes his receiver from its supporting hook or cradle to complete the desired connection. Shortly after the signaling circuit just traced is completed, the slow-to-operate relay R280, which is normally shunted by the condenser 284 in series with the exchange battery, operates. This relay, in operating, opens, at its contacts 281, the special signal circuit, whereby the signal is terminated. At its contacts 282, the relay R280 opens the path including the condenser 284 over which the exchange battery is normally connected in shunt with its winding, thereby to render itself fast to release.

As indicated above, the desired conversational circuit is completed when the calling subscriber at the substation A again removes the receiver provided at this substation from its supporting hook or cradle. With the arrangement illustrated, talking battery is supplied to the line 10 through the windings of the line relay R220, and the reverting call switch 35 is held operated until the connection is released at both the calling and called substations. More specifically, when the receivers respectively provided at the substations A and B are restored to their respective supporting hooks or cradles, the calling loop circuit is interrupted to cause the deenergization and release of the line relay R220. This relay, in releasing, opens, at its contacts 221, the operating circuit for the hold relay R230. The relay R230, in releasing, disconnects the private or release conductor 12c from ground, thereby to cause the release of the connector switch 25, the finder switch 20, and the line circuit 10a in the usual manner. At its contacts 231, the relay R230 connects the private conductor 12c through the re-

sistor 236 to the negative terminal of the exchange battery, whereby the reverting call switch is marked as idle in the bank contacts of the various connector switches. At its contacts 233, the relay R230 opens the previously traced locking circuit for the relay R270. At its contacts 235 the relay R230 completes a circuit extending through the contacts 264, for energizing the release magnet 296. When this magnet is energized, the wipers 293 and 294 are returned to their respective normal positions in the usual manner. When the switch 290 is thus normalized, the off-normal springs 297 are moved out of engagement to deenergize the relays R250 and R260. The relay R270, in restoring, opens the operating circuit for the relay R280, and a further point in the special signaling circuit traced above. Thus, the reverting call switch 35 is fully released.

From the above explanation it will be understood that the ringers respectively provided at the calling and called substations associated with the same multiparty line may, in certain instances, be arranged for energization over different sides of the line. Accordingly, the ringer provided at the calling substation is not energized during the ringing operation and the calling subscriber is not signaled as to when the call is answered. In such case the calling subscriber, after hanging up to initiate the ringing operation in the manner just described, waits a reasonable time interval and then picks up his receiver to again establish a connection with the line. If during this interval the call is answered at the called substation, the special signal transmitted to this substation serves to inform the answering party that the call is of the reverting type. On the other hand, if the subscriber at the calling substation removes the receiver provided at this substation from its supporting hook or cradle before the call is answered, the current transmitted through the receiver provided at this substation from the tone current source 46 serves to signal the calling subscriber that the call has not been answered. In such case the calling subscriber may either abandon the call to cause the release of the equipment in the manner explained above, or may hold the connection until the call is answered.

Referring now more particularly to Fig. 3 of the drawings, the system there illustrated comprises a plurality of subscribers lines which are terminated in line jacks at the operator's switchboard of a manual exchange. Thus, the subscribers line 50 is illustrated as extending to a line jack 313 which is provided at one of the operator's positions of an operator's switchboard in the manual office. The line jack 313 forms a part of a line circuit 55 which also includes the line relay R300, the sleeve relay R310 and the line signal lamp 302. Certain of the lines terminating at the operator's switchboard are of the multiparty type. Thus, the line 50 is illustrated as serving the two substations D and E. For the purpose of setting up connections between the various subscribers lines of the system, each operator's position at the switchboard is equipped with an operator's cord circuit. Thus, at the position wherein the line jack 313 is located, there is provided an operator's cord circuit 60 which is illustrated as comprising an answer plug 322, an operator's telephone set 328, an answer key 321, a pair of ringing control keys 342 and 365, a supervisory signal lamp 354, and seven supervisory and ringing control relays, R320, R330, R340, R350, R370, R385 and R390. The cord cir-

cuit further comprises a ringing code selecting switch 360 of the well-known minor type. This switch includes a single set of contacts 361 of eleven points, a wiper 362, an operating magnet 363 for driving the wiper 362 over its associated contacts, a release magnet 364, and a pair of off-normal springs 366. The contacts of this switch terminate ten ringing leads which are arranged to be connected to the high potential terminal of a ringing current generator 70 through operation of a cyclically operating ringing interrupter 65. This interrupter may be of any desired arrangement and functions to impress the voltage of the ringing current generator 70 upon the ten code leads for differently coded periods of each ringing cycle. Provisions are also made in the ringing interrupter 65 for impressing a ground pulse on the pickup lead C377 at the beginning of each ringing cycle. For the purpose of directly controlling the code selecting switch 360 to select any one of the ten ringing leads terminating in the contacts thereof, there is provided a calling device 380, which is arranged to be connected in circuit with the operating magnet 363 over a circuit controlled by the key 375. For the purpose of transmitting a special signal over calling ones of the multiparty lines in setting up reverting call connections, there is further provided in association with the operator's cord circuits, a special tone current source 353. This source may, for example, comprise an alternating current generator having a predetermined output frequency within the audio range.

Referring now more particularly to the operation of the apparatus, illustrated in Fig. 3 of the drawings, to set up a reverting call connection between two substations associated with the same line, it may be assumed that a call intended for the substation D is initiated at the substation E, and, further, that the line 50 serving these substations is arranged for bridged ringing. When the call is initiated at the substation E, a loop circuit including the winding of the line relay R300 is completed in the usual manner. This relay, in operating, completes, at its contacts 391, an obvious circuit for energizing the line signal lamp 302. The operator attending the position at which the jack 313 is terminated, upon observing the lighted condition of the lamp 302, is informed that a call is present on the line 50 which should be answered. To answer the call, the operator inserts the answer plug 322 in the jack 313. In response to this operation the line conductors 50a and 50b are connected through the tip and ring contacts of the jack 313 and the plug 322 to the line conductors of the operator's cord circuit. In addition, a circuit is completed at the sleeve contacts 325 and 316 for energizing the cut-off relay R310 in series with the release relay R320. The relay R310, in operating, opens its contacts 311 and 312, thereby to disconnect the windings of the line relay R300 from the conductors of the line 50. The operating circuit for the relay R300 is thus broken, and this relay restores to open its contacts 391, thereby to de-energize the signal lamp 302. The relay R320 in operating, opens a point in the circuit for energizing the release magnet 364. After inserting the plug 322 in the jack 313, the operator may actuate the key 327 to its off-normal position in order to connect the telephone set 328 to the line 50 and thus establish a talking circuit with the calling substation E. After this circuit is established, the operator may converse with the calling subscriber and ascertain the

party desired. Upon ascertaining that the substation D is desired by the calling subscriber, the operator may operate the key 342 to its off-normal position for the purpose of interrupting the ringing current circuit, operate the key 375 to its off-normal position to prepare the operating circuit for the magnet 363, and actuate the calling device 380 to the position corresponding to the code designating the desired substation D. When the key 375 is operated to its off-normal position a circuit including the contacts 375a and the pulsing springs 380a is completed for energizing the relay R385. This relay, in operating, opens a point in the circuit for energizing the magnet 363. Assuming that the fifth ringing code is assigned to the substation D, the operator dials the digit 5 to transmit five current pulses through the engaged contacts of the key 375 and the winding of the magnet 363. Thus, when the dial of the calling device is moved off-normal, the off-normal springs 380b are closed to complete an obvious operating circuit for the relay R390. The relay R390, in operating, prepares the circuit for energizing the magnet 363. During the return movement of the dial five current pulses are transmitted by the relay R385 to the magnet 363 over a circuit including the contacts 390 and 391, and the contacts 375b of the key 375. When the dial of the calling device is returned to its normal position, the off-normal springs 380b are disengaged to deenergize the relay R390. This relay, in releasing, opens, at its contacts 391, a further point in the operating circuit for the magnet 363. Each time the magnet 363 is energized, it cooperates with its associated ratchet and pawl mechanism to advance the wiper 362 one step so that at the conclusion of the digit this wiper is left standing in engagement with the contact terminating the code 5 ringing lead. When the wiper 362 is moved off normal, the off-normal springs 366 are operated into engagement to prepare a circuit for energizing the release magnet 364. After the ringing code is thus selected, the operator may open the circuit for energizing the magnet 363 and de-energize the relay R385 by restoring the key 375 to its normal position. Following this operation, and in order to initiate the ringing operation, the operator may restore the key 342 to normal and operate the key 365 to its off-normal position. After the key 365 is operated to its off-normal position, a ground pulse is transmitted over the pickup pulse lead C377 and through the springs 365b and the contacts 371 to energize the start relay R370 at the beginning of the next cycle of operation of the coding relays embodied in the ringing interrupter 65. When thus energized the relay R370 operates and locks to ground through the contacts 372 and the switch springs 365a. After this locking circuit is completed, the relay R370 opens its operating circuit and disconnects ground from the pickup lead C377 at its contacts 371. At its contacts 372, the relay R370 completes the circuit for transmitting ringing current of the code 5 over the calling line 50 to energize the signal device provided at the called substation D. The circuit traversed by this current extends from one terminal of the ringing current generator 70 through the contacts of the coding relays embodied in the interrupter 65 and by way of the code 5 ringing lead, the wiper 362, the lower winding of R330, the contacts 373, 334 and 344, the contacts 324 and 315, the line conductor 50b, the ringer and condenser bridged across the conductors of the line 50 at

the called substation D, the conductor 50a, the contacts 314 and 323, the switch springs 343, the contacts 332 and the exchange battery to the other terminal of the ringing current source. A portion of this ringing current is also directed through the ringers respectively provided at the other substations associated with the line 50. The coded character of the signals produced by this current indicates, however, that the call is intended for the substation D.

When the call is answered at the called substation D, a direct current bridge is connected between the conductors of the line 50 to complete a circuit for energizing the ring cut-off relay R330. This circuit extends from the negative terminal of the exchange battery through the ringing current generator and by way of certain of the contacts of the code interrupter relays, the code 5 ringing lead, the wiper 362, the lower winding of R330, the contacts 373, 334, 344, 324 and 315, the conductor 50b, the direct current bridge across the conductors of the line 50, the conductor 50a and the contacts 314, 323, 343 and 332 to the grounded terminal of the exchange battery. When thus energized the relay R330 first operates to complete a locking circuit for itself, this locking circuit extending from ground through the lower winding of R310 and by way of the contacts 316, 325 and 336, and the upper winding of R330 to battery. After this circuit is completed, the relay R330 completes its operation to open, at its contacts 332 and 334, two points in the above-traced ringing circuit and two points in its own operating circuit. At its contacts 333 and 335, the relay R330 bridges the windings of the combined battery feed and supervisory relay R340 across the conductors of the line 50. At its contacts 337, the relay R330 completes an obvious circuit for energizing the slow-to-release relay R350. At its contacts 331, the relay R330 completes the previously mentioned circuit for impressing the voltage of the special tone current source 353 upon the loop circuit extending to the called substation D. More specifically, current derived from the source 353 is transmitted over the line 50 to energize the receiver provided at the substation D over a circuit which includes the condenser 338, the contacts 331, 352, 333, 343, 323 and 314, the conductor 50a, the receiver provided at the substation D, the conductor 50b, the contacts 315, 324, 344 and 335, the lower winding of R340, and the exchange battery to the grounded terminal of the source 353. This current, as reproduced by the receiver provided at the substation D, serves to inform the party answering the call at the substation D that the answered call is of the revertive type.

When its windings are bridged across the conductors of the line 50 in the manner explained above, the relay R340 is energized over the loop circuit including this line, and operates to open, at its contacts 341, a point in the circuit for energizing the supervisory lamp 354. Shortly following the operation of the relay R330, the slow-to-operate control relay R350 operates to open, at its contacts 352, the above-traced circuit for energizing the receiver provided at the substation D with current derived from the current source 353. The special signal transmitted to the called substation to indicate the character of the call answered, is thus terminated. At its contacts 351, the relay R350 prepares the above-mentioned circuit for energizing the supervisory lamp 354.

The desired conversational circuit between the

calling and called substations is completed when the calling party at the substation E again removes the receiver provided at this substation from its supporting hook or cradle, thereby operatively to associate the telephone set in use at this substation with the line 50. In this regard it will be apparent that when the lines are arranged for bridged ringing, the calling party is informed that the call is answered when the ringing operation is arrested. After the connection is fully completed, in the manner just described, talking battery is supplied to the transmitters provided at the calling and called substations through the windings of the relay R340.

The release of the connection and of the operator's cord circuit 60 is, of course, controlled by the operator attending the position at which this circuit is provided. More specifically, when the call is cleared out at both the calling and called substations, the loop circuit extending by way of the line 50 and through the windings of the line relay R340 is interrupted. The relay R340 is thus deenergized and restores to complete, at its contacts 341, the above-mentioned circuit for energizing the supervisory lamp 354, this circuit extending from ground by way of the contacts 351 and 341, and the filament of the lamp 354 to battery. The resulting illumination of this lamp serves to inform the operator attending the position at which the cord circuit 60 is provided, that the connection is ready to be released. In order to release the connection, the operator restores the key 365 to its normal position to open the operating and locking circuits for the relay R310, and withdraws the answer plug 322 from the line jack 313. In response to the last-mentioned operation, the previously traced circuits for energizing the cut-off relay R310 in series with the parallel-connected relays R320 and R330 are broken, causing all three of these relays to restore. The relay R330, in releasing, opens the operating circuit for the relay R350, causing the latter relay to restore and open the circuit for energizing the supervisory lamp 354. Thus, all of the illustrated relays of the operator's cord circuit are restored to normal. The relay R320, in releasing, completes, at its contacts 321, a circuit extending through the off-normal springs 366 for energizing the release magnet 364. When this magnet is energized, the wiper 362 of the code selecting switch 360 is restored to normal position in the usual manner. Further, the release of this switch results in the disengagement of the off-normal springs 366 to deenergize the release magnet 364. Following the release of the code selecting switch in the manner just explained, the operator's cord circuit is fully restored to normal.

Although the arrangement illustrated in Fig. 3 of the drawings has been described with reference to the use of bridged ringing in signaling the substations associated with the multiparty lines of the system, it will be understood that by providing an arrangement similar to that incorporated in the reverting call switch 35 for selectively associating either the tip contact or the ring contact of the answer plug 322 with the ringing lead extending to the wiper 362 of the code selecting switch, the circuit may be adapted for use in signaling over multiparty lines arranged for divided ringing. It will also be understood that with the operator's cord circuit 60 equipped to signal over lines arranged for divided ringing, the special signal transmitted over a line of this character in setting up a

reverting call connection will not only serve to signal an answering called party of the character of the call answered, but in each instance where such a call is, in effect, answered at the calling substation, will serve to inform the calling subscriber that the call has not previously been answered at the called substation. It will further be apparent that the operator's cord circuit 60 may include the usual provisions for setting up connections between two substations associated with different subscribers' lines. In the interests of simplifying the disclosure, however, the conventional portion of the cord circuit, namely, that utilized in establishing a talking circuit between two different lines, has been 15 omitted.

While there have been described what are at present considered to be the preferred embodiments of the invention, it will be understood that various modifications may be made therein, and it is intended to cover in the appended claims, all such modifications as fall within the true spirit and scope of the invention.

What is claimed is:

1. In a telephone system, a multiparty subscribers' line, means for selectively signaling the substations associated with said line in setting up reverting call connections between said substations, and means comprising a relay which is energized over said line in response to the answering of a reverting call at one of said substations for transmitting a signal to the answering substation.

2. In a telephone system, a multiparty subscribers' line, means for selectively signaling the substations associated with said line in setting up reverting call connections between said substations, and means comprising a relay which is energized over said line in response to the answering of a reverting call at one of said substations for indicating to the answering party that the answered call is a reverting call.

3. In a telephone system, a multiparty subscribers' line, means for selectively signaling the substations associated with said line in setting up reverting call connections between said substations, and means operative in response to the answering of a reverting call at one of said substations for transmitting a signal of limited duration to the answering substation.

4. In a telephone system, a multiparty subscribers' line, means for selectively signaling the substations associated with said line in setting up reverting call connections, means operative in response to the answering of a reverting call at one of said substations for transmitting a signal to the answering substation, and means operative in response to operation of said last-named means for terminating said signal after a predetermined time interval.

5. In a telephone system, a subscribers' line, a pair of substations associated with said line, means for transmitting ringing current to a called one of said substations in setting up a connection between said substations, and means comprising a relay which is energized over said line in response to the answering of the call at said called substation for indicating to the answering party that the answered call is a reverting call.

6. In a telephone system, a subscribers' line, a pair of substations associated with said line, means for transmitting ringing current to a called one of said substations in setting up a connection between said substations, and means comprising a relay which is energized over said line in re-

sponse to the answering of the call at said called substation for arresting the transmission of ringing current over said line and for indicating to the answering party that the answered call is a reverting call.

7. In a telephone system, a subscribers' line, a pair of substations associated with said line, means for transmitting ringing current to a called one of said substations in setting up a connection between said substations, and means comprising a relay which is energized over said line in response to a call answering operation performed at one of said substations for arresting the transmission of ringing current over said line and for impressing a predetermined signal voltage upon said line.

8. In a telephone system, a subscribers' line, a pair of substations associated with said line, means for transmitting ringing current to a called one of said substations in setting up a connection between said substations, and means operative in response to a call answering operation performed at one of said substations for arresting the transmission of ringing current over said line and for impressing a predetermined signal voltage upon said line, whereby the answering party is informed that the call is a reverting call if the call is answered at the called substation and is informed that the call has not been answered at the called substation if the call answering operation is performed at the calling substation.

9. In a telephone system, a subscribers' line, a pair of substations associated with said line, means for transmitting ringing current to a called one of said substations in setting up a connection between said substations, means operative in response to a call answering operation performed at one of said substations for arresting the transmission of ringing current over said line and for impressing a predetermined signal voltage upon said line, and means operative in response to operation of said last-named means for removing said signal voltage from said line after a predetermined time interval.

10. In an automatic telephone system, a plurality of lines, automatic switching apparatus for setting up connections between said lines and including means controllable over a calling multiparty line for impressing ringing voltage on the calling line to signal a called substation associated with the calling line, and means comprising a relay which is energized over said line in response to the answering of the call at one of the substations associated with said calling line for transmitting a special signal to the answering substation.

11. In an automatic telephone system, a plurality of lines, automatic switching apparatus for setting up connections between said lines and including means controllable over a calling multiparty line for impressing ringing voltage on the calling line to signal a called substation associated with the calling line, and means comprising a relay which is energized over said line in response to the answering of the call at the called substation for indicating to the answering party that the answered call is a reverting call.

12. In an automatic telephone system, a plurality of lines, automatic switching apparatus for setting up connections between said lines and including means controllable over a calling multiparty line for impressing ringing voltage on the calling line to signal a called substation associated with the calling line, means operative in response to the answering of the call at one of

the substations associated with said calling line for removing ringing voltage from said calling line and for impressing a predetermined signal voltage upon said calling line, and means controlled by said last-named means for removing said signal voltage from said calling line after a predetermined time interval.

13. In an automatic telephone system, a plurality of lines including a multiparty subscribers line, ringing apparatus operative to provide ringing voltages having different station indicating characteristics individually corresponding to the substations associated with said multiparty line, a reverting call switch, automatic switching apparatus for setting up connections between said lines and including a numerical switch directly controllable over said multiparty line from a calling substation associated therewith to route a connection to said reverting call switch, said reverting call switch being directly controllable over said connection from said calling substation to impress the ringing voltage corresponding to a called substation upon said multiparty line and including means operative in response to the answering of the call at a substation associated with said multiparty line for removing the ringing voltage from said multiparty line and for impressing a predetermined signal voltage upon said multiparty line.

14. In an automatic telephone system, a plurality of lines including a multiparty subscribers line, ringing apparatus operative to provide ringing voltages having different station indicating characteristics individually corresponding to the substations associated with said multiparty line, a reverting call switch, automatic switching apparatus for setting up connections between said lines and including a numerical switch directly controllable over said multiparty line from a calling substation associated therewith to route a connection to said reverting call switch, said reverting call switch being directly controllable over said connection from said calling substation to impress the ringing voltage corresponding to a called substation upon said multiparty line and including means operative in response to the answering of the call at said called substation for transmitting a signal to the answering party indicating that the answered call is a reverting call.

15. In an automatic telephone system, a plurality of lines including a multiparty subscribers line, ringing apparatus operative to provide ringing voltages having different station indicating characteristics individually corresponding to the substations associated with said multiparty line, a reverting call switch, automatic switching apparatus for setting up connections between said lines and including a numerical switch directly controllable over said multiparty line from a calling substation associated therewith to route a connection to said reverting call switch, said reverting call switch being directly controllable over said connection from said calling substation to impress the ringing voltage corresponding to a called substation upon said multiparty line and including a ring cut-off relay and a slow-to-operate control relay sequentially operative in the order named in response to the answering of the call at one of the substations associated with said multiparty line, and means controlled by said relays for removing the ringing voltage from said multiparty line and for transmitting a signal of limited duration over

said multiparty line to the answering substation.

16. In combination with a plurality of ringing voltage sources, a reverting call switch having a trunk extending thereto and comprising means directly controllable over said trunk for impressing a selected one of said voltages upon said trunk, and means comprising a relay which is controllable over said trunk after the selected ringing voltage has been impressed thereon for removing the selected ringing voltage from said trunk and for impressing a predetermined signal voltage upon said trunk.

17. In combination with a plurality of ringing voltage sources, a reverting call switch having a trunk extending thereto and comprising means directly controllable over said trunk for impressing a selected one of said voltages upon said trunk, and means controllable over said trunk for removing the selected ringing voltage from said trunk and for transmitting a signal of limited duration over said trunk.

18. In combination with a plurality of ringing voltage sources, a reverting call switch having a trunk extending thereto and comprising means directly controllable over said trunk for impressing a selected one of said voltages upon said trunk, means controllable over said trunk for removing the selected ringing voltage from said trunk and for impressing a predetermined signal voltage upon said trunk, and means operative in response to operation of said last-named means for removing said signal voltage from said trunk after a predetermined time interval.

19. In combination with a plurality of ringing voltage sources, a reverting call switch having a trunk extending thereto and comprising means directly controllable over said trunk for impressing the voltage of a selected one of said sources upon said trunk, a ring cut-off relay and a slow-to-operate control relay sequentially operative in response to the completion of a loop circuit including said trunk, and means controlled by said relays for removing the ringing voltage from said trunk and for transmitting a special signal of limited duration over said trunk.

20. In combination with a plurality of ringing voltage sources, a reverting call switch having a trunk extending thereto and comprising means directly controllable over a loop circuit including said trunk and operative in response to the interruption of said loop circuit for impressing the voltage of a selected one of said sources upon said trunk, a ring cut-off relay and a slow-to-operate control relay sequentially operative in response to the recompletion of said loop circuit, and means controlled by said relays for removing the ringing voltage from said trunk and for transmitting a special signal of limited duration over said trunk.

21. In a telephone system, an operator's switchboard, a multiparty subscribers line terminating at said switchboard, and an operator's cord circuit including means for selectively signaling the substations associated with said line in setting up reverting call connections between said substations, and means comprising a relay which is energized over said line in response to the answering of a reverting call at one of said substations for transmitting a special signal to the answering substation.

22. In a telephone system, an operator's switchboard, a multiparty subscribers line terminat-

ing at said switchboard, and an operator's cord circuit including means for selectively signaling the substations associated with said line in setting up reverting call connections between said substations, means operative in response to the answering of a reverting call at one of said substations for transmitting a special signal to the answering substation, and means operative in response to operation of said last-named means for terminating said signal after a predetermined time interval.

23. In a telephone system, a operator's switchboard, a multiparty subscriber's line terminating at said switchboard, and an operator's cord circuit including means for selectively signaling the substations associated with said line in setting up reverting call connections between said substations, a ring cut-off relay and a slow-to-operate control relay sequentially operative in the order named in response to the answering of a reverting call at one of said substations, and means controlled by said relays for transmitting a special signal of limited duration over said line to the answering substation.

24. In a telephone system, a plurality of ringing voltage sources having different station indicating characteristics, an operator's switchboard, a multiparty subscriber's line terminating at a line jack provided at said operator's switchboard, and an operator's cord circuit including an answer plug adapted to be inserted into said jack to answer a call initiated at one of the substations associated with said line, a ringing voltage selecting switch having a normal setting and selectively operable to any one of a plurality of off-normal settings to impress a selected one of said voltages upon said line in setting up reverting call connections between said substations, means operative in response to the answering of a reverting call at one of said substations for removing the selected ringing voltage from said line and for transmitting a special signal to the answering substation, and means operative in response to removal of said answer plug from said jack for normalizing said switch.

25. In a telephone system, a plurality of ringing voltage sources having different station indicating characteristics, an operator's switchboard, a multiparty subscriber's line terminating at a line jack provided at said operator's switchboard, and an operator's cord circuit including an answer plug adapted to be inserted into said jack to answer a call initiated at one of the substations associated with said line, an impulse responsive ringing voltage selecting switch having a normal setting and operative to any one of a plurality of off-normal settings to impress a selected one of said voltages upon said line in response to impulses transmitted thereto, thereby selectively to signal said substations in setting up reverting call connections therebetween, said switch including a release magnet operative to cause said switch to restore to normal, means for transmitting impulses to said switch, means operative in response to the answering of a reverting call at one of said substations for removing the selected ringing voltage from said line and for transmitting a special signal over said line to the answering substation, and means operative in response to removal of said answer plug from said jack for energizing said release magnet.

26. In a telephone system, a plurality of ringing voltage sources having different station indicating characteristics, an operator's switch-

board, a multiparty subscriber's line terminating at a line jack provided at said operator's switchboard, and an operator's cord circuit including an answer plug adapted to be inserted into said jack to answer a call initiated at one of the substations associated with said line, an impulse responsive ringing voltage selecting switch having a normal setting and operative to any one of a plurality of off-normal settings to impress a selected one of said voltages upon said line in response to impulses transmitted thereto, thereby selectively to signal said substations in setting up reverting call connections therebetween, said switch including a release magnet operative to cause said switch to restore to normal, means for transmitting impulses to said switch, means operative in response to the answering of a reverting call at one of said substations for removing the selected ringing voltage from said line and for transmitting a special signal over said line to the answering substation, and means comprising a relay controlled over a circuit including one of the contacts of said plug for energizing said release magnet in response to removal of said plug from said jack.

27. In a telephone system, a plurality of ringing voltage sources having different station indicating characteristics, an operator's switchboard, a multiparty subscriber's line terminating at a line jack provided at said operator's switchboard, and an operator's cord circuit including a plug adapted to be inserted into said jack in handling calls involving the substations associated with said line, a ringing voltage selecting switch having a normal setting and selectively operable to any one of a plurality of off-normal settings to impress a selected one of said voltages upon said line, and means operative in response to removal of said plug from said jack for normalizing said switch.

28. In a telephone system, a plurality of ringing voltage sources having different station indicating characteristics, an operator's switchboard, a multiparty subscriber's line terminating at a line jack provided at said operator's switchboard, and an operator's cord circuit including a plug adapted to be inserted into said jack in handling calls involving the substations associated with said line, a ringing voltage selecting switch having a normal setting and selectively operable to any one of a plurality of off-normal settings to impress a selected one of said voltages upon said line, and means comprising a relay controlled over a circuit including one of the contacts of said plug for causing the release of said switch in response to removal of said plug from said jack.

29. In a telephone system, a plurality of ringing voltage sources having different station indicating characteristics, an operator's switchboard, a multiparty subscriber's line terminating at a line jack provided at said operator's switchboard, and an operator's cord circuit including a plug adapted to be inserted into said jack in handling calls involving the substations associated with said line, an impulse responsive ringing voltage selecting switch having a normal setting and operative to any one of a plurality of off-normal settings to impress a selected one of said voltages upon said line in response to impulses transmitted thereto, said switch including a release magnet operative to cause said switch to restore to normal, means for transmitting impulses to said switch, and means operative in response to re-

moval of said answer plug from said jack for energizing said release magnet.

30. In combination with a plurality of ringing voltage sources having different station indicating characteristics, an operator's cord circuit including a line connect plug having a pair of line contacts and a control contact, a ringing voltage selecting switch having a normal setting and selectively operable to any one of a plurality of off-normal settings to impress a selected one of said voltages upon said line contacts, and means controlled over a circuit including said control contact for automatically restoring said switch to normal.

31. In combination with a plurality of ringing voltage sources having different station indicating characteristics, an operator's cord circuit including a line connect plug having a pair of line contacts and a control contact, an impulse responsive ringing voltage selecting switch having a normal setting and operative to any one of a plurality of off-normal settings to impress a selected one of said voltages upon said line in response to impulses transmitted thereto, said switch including a release magnet operative to cause said switch to restore to normal, means for transmitting impulses to said switch, and means controlled over a circuit including said control contact for energizing said release magnet.

32. In combination with a plurality of ringing voltage sources having different station indicating characteristics, an operator's cord circuit including a line connect plug having a pair of line contacts, means for selectively impressing said voltages upon said contacts, and means controlled over a circuit including said contacts for removing a selected one of said voltages from said contacts and for impressing a predetermined signal voltage upon said contacts.

33. In combination with a plurality of ringing voltage sources having different station indicating characteristics, an operator's cord circuit including a line connect plug having a pair of line contacts, means for selectively impressing a ring cut-off relay and a slow-to-operate control relay sequentially operative in the order named and controlled over said contacts for removing a selected one of said voltages from said contacts and for impressing a predetermined signal voltage upon said contacts for a predetermined time interval, a battery feed relay including windings connected to said contacts in response to operation of said ring cut-off relay, a signal device, and a circuit controlled by said control relay and said battery feed relay for energizing said signal device only after a reverting call connection established through operation of said cord circuit is released.

34. In combination with a plurality of ringing voltage sources having different station indicating characteristics, an operator's cord circuit including a line connect plug having a pair of line contacts and a control contact, a ringing voltage selecting switch having a normal setting and selectively operable to any one of a plurality of off-normal settings to impress a selected one of said voltages upon said line contacts, means con-

trolled over a circuit including said line contacts for removing a selected one of said voltages from said line contacts and for impressing a predetermined signal voltage upon said line contacts, and means comprising a relay controlled over a circuit including said control contact for automatically restoring said switch to normal.

35. In a telephone system, an operator's switchboard, a multiparty subscribers line terminating at a line jack provided at said switchboard, and an operator's cord circuit including an answer plug adapted to be inserted into said jack to answer a call initiated at one of the substations associated with said line, means for selectively signaling said substations in setting up reverting call connections between said substations, a signal device, and means controlled over said line for energizing said signal device only when a reverting call connection set up through operation of said cord circuit is released.

36. In a telephone system, a line, a plurality of substations associated with said line, means for transmitting ringing current over said line to a called one of said substations in setting up a connection between said substations, means for automatically arresting the transmission of ringing current over said line when the call is answered, and means for transmitting a distinctive signal to the answering party when the call is answered, whereby the answering party is informed that the answered call is a reverting call if the call is answered at the called substation and is informed that the call has not been answered at the called substation if the call answering operation is performed at the calling substation.

37. In a telephone system, a line, a plurality of substations associated with said line, means for transmitting ringing current over said line to a called one of said substations in setting up a connection between said substations, means for automatically arresting the transmission of ringing current over said line when the call is answered, means for transmitting a distinctive signal to the answering party when the call is answered, whereby the answering party is informed that the answered call is a reverting call if the call is answered at the called substation and is informed that the call has not been answered at the called substation if the call answering operation is performed at the calling substation, and means for automatically terminating said signal a predetermined time interval after the transmission of ringing current over said line is arrested.

38. In a telephone system, a multiparty subscriber line, means for selectively signaling the substations associated with said line in setting up reverting call connections between said substations, and means for transmitting a distinctive signal over said line to the party answering a reverting call, whereby the answering party is informed that the answered call is a reverting call if the call is answered at the called substation and is informed that the call has not been answered at the called substation if the call answering operation is performed at the calling substation.
